UNITED STATES PATENT OFFICE.

ERNEST F. T. LUNDQUIST, OF CHICAGO, ILLINOIS, ASSIGNOR TO ILLINOIS MODERN MACHINE COMPANY, OF CHICAGO, ILLINOIS.

BUTTON-MAKING MACHINE.

No. 918,177.

Specification of Letters Patent. Patented April 13, 1908.

Application filed March 6, 1908. Serial No. 419,420.

To all whom it may concern:

Be it known that I, ERNEST F. T. LUNDQUIST, a citizen of the United States of America, and a resident of Chicago, county of 5 Cook, and State of Illinois, have invented certain new and useful Improvements in Button-Making Machines, of which the following is a specification.

My invention relates to presses such as are 10 commonly used in making buttons composed of a plurality of elements and has for its object improvement in the construction and operation of its various parts, and especially to the means for controlling the position of 15 the die on the upper head.

In the accompanying drawings Figure 1 is a side elevation of the machine; Figs. 2 and 3 are sections on line 2—3 of Fig. 1 showing the parts in two positions; Fig. 4 is a perspective view of the die-controlling arm; and Fig. 5 is an enlarged section on line 5—5 of Fig. 4.

In the said drawings A is a base to which is secured a vertical pin B (Figs. 2 and 3) by 25 means of a dowel A¹ (Fig. 1). At the upper end of the pin B is secured a head piece C by means of a second dowel A². Pivoted on the pin B, between the base A and the head C, is a swinging die-holder D, upon the lateral 30 arms D¹ of which are the lower dies E and E¹. Between the base A and head C is a second pin F secured to base and head by suitable dowel pins. This second pin F acts to strengthen or stiffen the connection between 35 head and base, and also to limit the movement of die-holder D by engagement between it and the arms D¹.

In guides in the head C is a reciprocating plunger G normally held in an elevated position 40 by the spring G¹. A cam-lever H serves to depress the plunger G. Slidably mounted on the lower end of the plunger G is a die G², the upward movement of which is limited by a collar G³ rigidly secured to the plunger G.

Pivoted in a hole in the plunger G is a controlling arm J, the lower end J² of which is 45 adapted to swing into contact with the lower part of the plunger G between the collar G³ and the upper die G². When the arm J is in this position the die G² is prevented from 50 sliding on the plunger rod G, but when the arm J is moved away by being swung on its pivot, the die G² is free to move up to the collar G³. At the upper end of the arm J is a 55 small transverse cut J¹ in which the upper

end of the spring G¹ rests. This cut has a flat (see Fig. 5) surface against which the spring G¹ presses, and this surface is so shaped or inclined relatively to the arm itself that the upward pressure of the spring G¹ acts to hold 60 the lower part J² into contact with the plunger G. The engagement of the spring G¹ with the notch or cut J¹ prevents the arm J from slipping out of its bearing in the plunger G. It will be apparent that by pressing the 65 spring G¹ downward slightly by hand the arm J may be freely removed.

The die-holder D and its arms are in the shape of a sector, and on one of the arms D¹ is a vertical pin K, the upper end of which 70 is adapted to engage the tip J³ at the extreme end of the arm J. When the die holder D is swung into the position shown in Fig. 3 with the lower die E under the upper die G², the pin K strikes the tip J³ to swing the arm 75 J on its pivot and move the curved part J² from between the die G² and the collar G³. In this condition, when the cam-lever H is moved to force the die G² against the lower die E, the upper die G² will slide up on the 80 stem or plunger G. When the die-holder D is swung into the position shown in Figs. 1 and 2 with die E¹ under die G² the pin K will be removed and the spring G¹ will bring the part J² between die G² and collar G³ and prevent such sliding of the die G² when the plunger is depressed.

It will be observed that by pivoting the controlling arm J upon the plunger G the lower or controlling part is always in the 90 proper vertical position to swing into the space between collar G³ and die G² irrespective of the vertical position of the plunger G. This is a matter of considerable convenience in operation as compared to similar devices now used. It will also be observed that the lower die frame is pivoted to swing transversely on the upright standard which holds the head C and plunger G, and that in swinging on this pivot the amount of 100 movement is limited by another part of this standard. That part of the standard which consists of the pin F is so related to the arms D¹ of the die-holder D, that when moved to one extreme one lower die is directly under 105 the upper die, and when moved to the other extreme the other lower die is under the upper die. This is a superior form of construction both in convenience of operating and in the general appearance of the machine. 110

What I claim is:

1. In a machine of the character described, a base, a standard consisting of a pin secured to said base, a head secured to the upper part 5 of the said pin, a vertically movable member supported by and guided in said head, a frame mounted upon said pin between the base and the head and arranged to swing about said pin as a center, a stop for limiting 10 the movement of said frame, said stop constituting a supplementary part of the standard, and a plurality of other members for coöperating with the vertically movable member supported on said frame and arranged 15 by the movement of the frame on its pivot.
2. In a machine of the character described, a vertically reciprocating plunger, a spring operating to cause said reciprocations in one 20 direction, a die carried by said plunger and movable thereon, and a controlling member carried by said plunger and arranged to prevent said die sliding thereon, said controlling member being normally held in operative 25 position by said spring.
3. In a machine of the character described, a vertically reciprocating plunger, a spring operating to cause said reciprocations in one direction, a die carried by said plunger and 30 movable thereon, a controlling member carried by said plunger and arranged to prevent said die sliding thereon, said controlling member being normally held in operative 35 position by said spring, a plurality of other dies arranged to be brought successively be-

neath the first mentioned die, and means associated with the last mentioned dies for moving said controlling member out of operative position.

4. In a machine of the character described, a vertically reciprocating and sliding die, a member for controlling the sliding action of said die, and a spring operating to reciprocate said die in one direction and also operating to normally hold said controlling member in operative position.

5. In a machine of the character described, a vertically reciprocating plunger, a die arranged to reciprocate with said plunger and to slide thereon, a spring for normally holding said plunger at its upper position, and a device pivoted on said plunger and operating to control the sliding of the die on the plunger, said device being provided with a notch engaged by said spring whereby the spring 50 acts to hold the device in operative position.

6. In a machine of the character described, a vertically reciprocating plunger, a spring for normally holding said plunger in its upper position, a die carried by and slidable on said plunger, and a device pivoted on said plunger and normally held by said spring in a position to prevent said die sliding on said plunger.

Signed at Chicago, Ill., this 27th day of 65
Feb. 1908.

ERNEST F. T. LUNDQUIST.
